UNITED STATES PATENT OFFICE.

ARTHUR J. SEYMOUR, OF ST. PAUL, MINNESOTA, ASSIGNOR TO AUTOMATIC ELECTRIC COMPANY, OF CHICAGO, ILLINOIS, A CORPORATION OF ILLINOIS.

SEMI-AUTOMATIC TELEPHONE SYSTEM.

1,377,225.

Specification of Letters Patent. Patented May 10, 1921.

Application filed March 18, 1919. Serial No. 283,466.

To all whom it may concern:

Be it known that I, ARTHUR J. SEYMOUR, a citizen of the United States of America, and a resident of St. Paul, in the county 5 of Ramsey and State of Minnesota, have invented certain new and useful Improvements in Semi-Automatic Telephone Systems, of which the following is a specification.

10 My invention relates in general to a so-called semi-automatic system in which it is desired to have interconnection between a manual and an automatic exchange and where it is therefore necessary to provide 15 the operator in the main exchange with means for connecting with and operating the automatic switches in the automatic section of the exchange.

More specifically my invention relates to 20 an improved trunk circuit for use by an operator in extending calls to an automatic exchange, having improved means for automatically switching an operator's calling device into and out of connection with said 25 trunk circuit to allow control of the switches. These and other features of my invention will be more fully pointed out in connection with the accompanying drawings in which—

Figure 1 shows a well known type of 30 manual cord circuit B together with a trunk circuit C accessible thereto. In the trunk circuit C is a calling device C. D. which is common to a plurality of trunk circuits similar to C, and adapted to be automatically 35 connected to each one as used and disconnected thereafter either automatically or at the operator's will, as will hereinafter more fully appear.

Fig. 2 shows an automatic selector 40 switch D individual to the trunk circuit C and controlled thereover and having access to a number of connector switches H of well known type which complete the connection to a called line. The selectors and 45 connectors of this system may be of any approved type such as the Strowger type of vertical and rotary switch, it being understood that any type of switch may be used and any type of cord circuit may be 50 used without departing from the spirit of my invention.

I will now describe the operations when the operator at cord circuit B receives a call for a subscriber in the automatic ex-

change. In such a call the operator at B 55 inserts the plug P into the jack P' associated with an outgoing trunk line to the automatic exchange. As soon as this plug is inserted, a circuit is closed for the relay 2 of the trunk circuit extending from ground 60 through said relay, sleeve of jack P' and plug P, low resistance relay 3 of the cord circuit and through a lamp 4 to battery. Relays 2 and 3 energize over this circuit, relay 2 operates to close a circuit through 65 springs 5, springs 6 and 7, and relay 8 to battery. Relay 2 also closes one point in a circuit of the relay 9 at springs 10, which circuit is not completed at this time. Relay 8 also energizes to open the talking circuit 70 at springs 11 and 12, closes a circuit for the guard lamp 13 at springs 14 and connects the calling device springs 16 across the called end of the trunk circuit through springs 11 and 15, relay 18, and the 75 springs 17.

The calling device C. D. is therefore connected across the trunk circuit in series with the line relay 20 of the selector D (Fig. 2) which energizes to close a circuit for 80 slow release relay 21 through its front contact. Relay 21 in the usual manner operates to prepare the circuits of the various magnets and relays of the switch D.

Now when the operator at cord circuit B 85 sees the guard lamp 13 lighted, she operates the calling device C. D. in accordance with the digits of the wanted subscriber's number. Before the operation of the calling device, the springs 22 and 23 are closed as 90 shown connecting ground to the series circuit of the calling device and the line relay of the switch D. It will be seen therefore that the relay 18 and the lower winding of relay 20 of switch D are short circuited 95 through ground so that the relay 18 does not energize at this time and relay 20 energizes by means of its upper winding only. Now when the calling device is first operated the spring 22 is moved out of engagement with the spring 23 by the engagement therewith of spring 24, thereby removing the original short circuit about relay 18 and the winding of relay 20 and substituting instead a direct short circuit about the winding of relay 18 only, so that the line relay 20 is now energized over the two sides of the line in series, with the calling device 100 105

and both its windings in series during impulses. The operation of the selector D and of the connector H will be explained only in general as the operation of such switches 5 is old in the art and therefore well known.

- The line relay 20 operates in response to the first digit of the called number to control the magnet 25 to step the wipers to a level of contacts, then relay 26 operates to close a 10 circuit for magnet 27 to step the wipers onto an idle set of contacts in the selected level, the relay 28 acting as a test relay to stop the operation of magnet 27 when such idle trunk is reached. Then the switching relay 29 is 15 operated to cut the connection through to the line relay of the connector switch H. The line relay 30 responds to the next digit to operate the vertical magnet 31 through contacts of slow relay 32 which remains energized during impulses. Magnet 31 raises the wipers of the switch H to some level of the bank and as the series relay 33 falls back after this digit, the circuit of the rotary magnet 34 is prepared. The operation of relay 20 by the next digit operates magnet 34 to 25 step the wipers to the contacts of the called line, relay 35 energizing in multiple with magnet 34 to hold the busy relay 36 connected to the private wiper so that if the line is busy said relay 36 will energize to 30 transmit a busy signal to the talking circuit. If the line is idle then relay 37 will energize after the relay 35 falls back and the called line is connected to the ringing circuit for 35 signaling purposes. When the called subscriber responds by removing his receiver, a circuit is completed for the ring cut off relay 38, which energizes to disconnect the ringing circuit and connects the back bridge 40 relay 39 across the called line. Relay 39 now energizes and reverses the connections of the line relay 30 with regard to the extended talking circuit, thereby reversing the direction of current flow in the trunk circuit 45 C (Fig. 1). When this reversal takes place a circuit is completed from ground through springs 23 and 22, relay 18, springs 15 and 11, springs 40 and 41, springs 42 and 43 and upper winding of relay 30 to battery. Therefore it will be seen that relay 18 is no longer short circuited but is energized over this 50 circuit in series with relay 30. Relay 18 upon energizing, closes a circuit from battery through springs 45, springs 46 and 47, relay 9, and springs 10 to ground. Relay 9 locks itself energized through springs 47 and 48 to battery and opens the circuit of the slow relay 8 at springs 6 and 7 and connects ground to one side of the talking circuit 55 through spring 6 and its front contact and back contact of relay 49. Relay 8 falls back at this time disconnecting the calling device C. D. from the trunk circuit C and at the same time a circuit is completed for the relay 60 49 from ground at the cord circuit B, through

the plug and jack, relay 49, springs 12 and 11, and upper winding of relay 30 to battery. Relay 49 on energizing closes the springs 50 and 51 in contact thereby completing a circuit for the supervisory relay 54 70 at the cord circuit, which operates to extinguish the lamp 4 by connecting battery through springs 55 thereby shorting the lamp and holding relays 3 and 2 energized.

Should the operator desire, as in most 75 cases she will, to disconnect the calling device as soon as the call is set up and before it is answered, then she will immediately press the non-locking key 56 as soon as she finishes operating the dial. In this case the 80 circuit of relay 9 is closed through the springs 56 instead of through the springs of relay 18 and relay 9 will lock as before explained to open the circuit of relay 8 at springs 6 and 7 and thus remove the calling 85 device from across the trunk. At the same time a circuit is closed as before from ground through springs 5, springs 6 and 57, springs 52 and 51, springs 58 and 59, springs 60 and 61, and upper winding of line relay 30 to 90 battery. This circuit prevents relay 30 from deenergizing and releasing the switches before the called man answers. In this case when the called man answers relay 49 is immediately energized due to the reversal of 95 current and the closure of its springs allows relay 54 at the cord circuit to operate and put out its supervisory signal.

It will be seen therefore that I have provided a very simple and efficient trunk circuit 100 for use from a manual cord circuit to an automatic switch and one which cuts the operations of the operator to a minimum. That is, when the operator seizes this trunk a calling device is automatically thrown 105 across the trunk which device may of course be common to a number of such trunks and the operator simply dials the number and then operates the key which disconnects the device and allows it to be used on another 110 trunk circuit and also prepares the circuits so that when the called subscriber responds, the talking circuit is cut through and proper supervision given. In addition I have so arranged this trunk circuit that in case the 115 operator does not operate the key but leaves the calling device across the trunk then the response of the called subscriber will automatically cut off the device as well as perform the other functions just as though the 120 key had been pressed first.

Having fully described and ascertained the features and aspects of my invention, what I consider to be new and desire to have protected by Letters Patent will be pointed 125 out in the appended claims.

What I claim as my invention is:

1. In a semi-automatic telephone system, a cord circuit, trunk lines accessible thereto, a calling device, means for automatically 130

associating said device with a trunk line when seized by the cord circuit, and means controlled by a called subscriber to whom a connection is extended for removing the calling device from the trunk line.

5 2. In a semi-automatic telephone system, a cord circuit, trunk lines accessible thereto, a calling device, a relay for automatically associating said device with a trunk line 70
10 when seized by the cord circuit, and means controlled by a called subscriber to whom a connection is extended for removing the calling device from the trunk line.

15 3. In a semi-automatic telephone system, a cord circuit, trunk lines accessible thereto, a calling device, electromagnetic means for automatically associating said device with a trunk line when seized by the cord circuit, and means controlled by a called subscriber to whom a connection is extended for removing the calling device from the trunk line.

20 4. In a telephone system, an operator's cord circuit, a supervisory signal therefor, 75
25 trunk lines accessible to said cord circuit and adapted to be seized thereby, means controlled by the seizure of one of said trunk lines for automatically connecting said calling device thereto, means controlled
30 by the operator for disconnecting said device from the trunk line, and means controlled by the response of a called subscriber for operating said signal.

35 5. In a telephone system, an operator's cord circuit, a supervisory signal therefor, 80
trunk lines accessible to said cord circuit and adapted to be seized thereby, electromagnetic means controlled by the seizure of one of said trunk lines for automatically
40 connecting said calling device thereto, means controlled by the operator for disconnecting said device from the trunk line, and means controlled by the response of a called subscriber for operating said signal.

45 6. In a telephone system, an operator's cord circuit, a supervisory signal therefor, 85
trunk lines accessible to said cord circuit and adapted to be seized thereby, a relay controlled by the seizure of one of said
50 trunk lines for automatically connecting said calling device thereto, means controlled by the operator for disconnecting said device from the trunk line, and means controlled by the response of a called subscriber for
55 operating said signal.

7. In a telephone system, an operator's cord circuit, a signal in the cord circuit, automatic switches accessible to said cord circuit, trunk lines leading to said switches, 90
60 a calling device common to said trunk lines, automatic means controlled by the seizure of one of said switches for connecting said calling device to the trunk line leading to said switch, said switch under control of
65 said calling device when controlled by the

operator to extend a connection to a called line, and means controlled by the subscriber on the called line for disconnecting the device from the trunk line and for operating a signal in the cord circuit.

70 8. In a telephone system, trunk lines, a calling device common to said trunk lines, means controlled by the seizure of one of said trunk lines for bringing said calling device into operative relation with the seized 75
trunk line, and means controlled either automatically or by the operator for removing the calling device from operative relation with the trunk.

8. In a telephone system, trunk lines, a calling device common to said trunk lines, means for seizing one of said trunk lines to extend a connection, means controlled by the seizure of said trunk line for connecting said calling device thereto, means controlled 85
by said calling device for extending the connection to a called subscriber, and means controlled by the called subscriber for disconnecting said calling device.

9. In a telephone system, trunk lines, a calling device common to said trunk lines, means for seizing one of said trunk lines to extend a connection, means controlled by the seizure of said trunk line for connecting said calling device thereto, means controlled 90
95 by said calling device for extending the connection to a called subscriber, and means controlled by the called subscriber for disconnecting said calling device while the connection is established.

10. In a telephone system, trunk lines, a calling device common to said trunk lines, means for seizing one of said trunk lines to extend a connection, means controlled by the seizure of said trunk line for connecting said calling device thereto, means controlled 95
100 by said calling device for extending the connection to a called subscriber, and means controlled by the called subscriber for disconnecting said calling device while the connection is established.

11. In a telephone system, trunk lines, a calling device common to said trunk lines, a cord circuit for seizing one of said trunk lines to extend a connection, means controlled by the seizure of said trunk line for connecting said calling device thereto, means controlled 105
110 by said calling device for extending the connection to a called subscriber, and means controlled by the called subscriber for disconnecting said calling device.

12. In a telephone system, trunk lines, a calling device common to said trunk lines, means for seizing one of said trunk lines to extend a connection, a relay controlled 115
110 by the seizure of said trunk line for connecting said calling device thereto, means controlled by said calling device for extending the connection to a called subscriber, and means controlled by the called subscriber for disconnecting said calling device.

13. In a telephone system, trunk lines, a calling device common to said trunk lines, means for seizing one of said trunk lines 120
125 to extend a connection, a relay controlled by the seizure of said trunk line for connecting said calling device thereto, automatic switches controlled by said calling device for extending the connection to a called 130

subscriber, and means controlled by the called subscriber for disconnecting said calling device.

14. In a telephone system, trunk lines, a cord circuit, a calling device common to said trunk lines, said trunk lines accessible to said cord circuit, means controlled by the connection of said cord circuit and one of said trunk lines for connecting the calling device to the trunk line, a relay for disconnecting the calling device from the trunk line, and a key for preventing the operation of said relay and disconnecting said calling device.
15. 15. In a semi-automatic telephone system in which a cord circuit, a trunk line and an automatic switch are successively connected to extend a connection to a called subscriber, a calling device, means for connecting the calling device to the trunk line when the cord and trunk line are first connected, a relay which operates when the called subscriber answers to disconnect the calling device, and a key for also disconnecting said calling device and rendering said relay inoperative.

16. In a telephone system, trunk lines, means for seizing one of said trunk lines to extend a connection, a calling device for said trunk lines, a relay for connecting said calling device to a trunk line when that trunk line is seized, another relay for disconnecting said calling device and for clos-

ing one of the conductors of said trunk line, and another relay for closing another conductor of said trunk line.

17. In a telephone system, a cord circuit, a signal therein, a trunk line accessible thereto, said trunk line having one point normally open and another point normally closed, a calling device for said trunk line, means controlled by the seizure of said trunk line for connecting said calling device thereto and for opening said normally closed point, automatic means for disconnecting said calling device and closing said normally closed point, and for then closing said normally open point to control said signal.

18. In a telephone system, a cord circuit having a plug and a signal, a trunk line having a jack, a calling device automatically connected to said trunk line when said plug is inserted in the jack, means controlled by said device for extending a connection from said trunk line to a called subscriber, a key for disconnecting said calling device, and means controlled by the called subscriber for operating said signal if the key has been pressed and for first disconnecting the calling device and then operating the signal if the key has not been pressed.

Signed by me at St. Paul, Ramsey county, State of Minnesota, this eleventh day of March, 1919.

ARTHUR J. SEYMOUR.
